NEGATIVE RESISTANCE

Edward H. Yonkers, Jr., Chicago, Ill.

Application July 22, 1930, Serial No. 469,869

REISSUED

2 Claims. (Cl. 250—36)

The present invention relates in general to electrical circuits, particularly those of the type known as negative resistance circuits for producing oscillating currents, the present invention 5 employing a function of the electrons thrown off from an incandescent cathode for this purpose.

One of the objects of my invention is to provide a device having negative electrical resistance characteristics, that is, a device wherein 10 the current varies inversely with the applied potential, and wherein this variation of current is attained by regulation of the velocity of flow of electrons between the various electrodes of the system.

15 Prior art devices known to me wherein negative resistance characteristics are present depend either upon gas ionization or upon the phenomenon known as secondary emission of electrons for their operation, as distinguished from my present invention wherein neither of these phenomena is employed, or essential to, the attainment of the functions of this device.

Further objects of this invention reside in the provision of a unitary structure capable of 25 convenient installation in electrical circuits for producing the desired results, and for carrying out the method here involved; the provision of a system and method of producing electrical oscillations referred to wherein the various electrodes of the device are appropriately mounted in a highly evacuated container conveniently of 30 transparent material, such as glass or the like, and provided with suitable lead-in wires capable of connection as desired in the circuit in which the device is to be used.

The foregoing and such other objects and advantages which may appear or be pointed out as 35 this description proceeds, are attained in a structural embodiment of the invention for carrying 40 the method and system into effect, illustrated in the accompanying drawing wherein:

Figure 1 is a composite view in longitudinal and transverse section illustrating one form of a device for carrying out the invention;

45 Figure 2 is a diagram illustrating the current characteristics of one of the devices of this invention;

Figure 3 is a diagrammatic view of an electrical circuit incorporating the features of this invention.

50 Referring now more particularly to the drawing and first to Figure 1, I have illustrated a highly evacuated envelope 5, which may be formed of a transparent material, such as glass, 55 and includes the enlarged bulb portion 6, pro-

vided with reduced ends 7 and 8, formed with inwardly directed axially aligned pedestals 9 and 9a, which serve as supporting elements for the lead-in wires and electrodes hereinafter described.

Extending through and supported by the pedestal 9 I provide a filamentary cathode 10, whose lead-in conductors 11 are connected so as to supply current for heating the cathode 10 to incandescence. In the structural embodiment 10 shown in Figure 1 for convenience I provide a grid 12, which latter is mounted preferably on the longitudinal axis of the device and is helical in form, that is, is formed of a coiled wire with the convolutions thereof slightly spaced apart. The 15 grid is supported on its conductor wire 13, which latter extends through the pedestal 9a and is connected in an electrical circuit as will be hereinafter described.

The grid 12, is itself surrounded by a system of 20 electrodes including the inner electrode 14 composed of the disks 15, which are thus perpendicular to the axis of the grid. The electrode 14 is provided with the collar 16 surrounding and supported by the pedestal 9, a lead-in wire 17 being 25 connected to said collar.

A fourth electrode is provided which comprises an annular plate 18, supported by arms 19 fixedly secured to a ring 20 surrounding and supported by the pedestal 9a. A lead-in wire 21 is connected to the ring 20. It will be understood that the electrode 18 is in the nature of a cylinder whose axis is coincident with the axis of the device.

The operating characteristics of the device are 35 determined by the geometry of the disc system or third electrode. The envelope 5 should be exhausted to such a degree of vacuum that no appreciable current is carried by gaseous ions when the required potentials are applied to the device. 40

If the cathode 10 is connected to earth and heated to incandescence and a positive potential is applied to the grid 12 there will be a flow of electrons from cathode 10 to grid 12. Some of these electrons will pass through the openings in the coiled portion of the grid and move toward the plates 15 of the third electrode 14. Their velocity upon reaching the boundaries of the third electrode will be determined by the potential of that electrode with respect to the cathode. Thus, 45 a stream of electrons will flow between the discs 15 of the third electrode with a velocity determined by the potential of said electrode.

Due to their mutual repulsion the electrons comprising this stream develop an additional 50

component of velocity perpendicular to the direction of the stream. Hence, the stream will spread toward the surfaces of the discs 15 and some of the electrons will strike the discs, thereby causing a negative current of electricity to flow from the third electrode 14. The magnitude of this current is an inverse function of the velocity of the stream of electrons which enters the space between the discs 15 of the third electrode provided the fourth electrode 18 is maintained at some suitable positive potential. This is because at high velocities the time required for the individual electrons to pass between the discs is small and their displacement toward the discs is therefore small, whereas, at low velocities their time between the discs is sufficiently long to permit a large portion of them to migrate to the discs. Thus, when the potential of the third electrode is high the current to it is small and the current to the fourth electrode is large and when the potential of the third electrode is low the current to it is large and that to the fourth electrode is small.

These characteristics can best be understood by reference to the curves shown in Figure 2 in which the ordinates represent electron currents to the third and fourth electrodes 14 and 18 and the abscissæ represent the potential of the third electrode 14. Curve A represents the current-potential characteristic of the third electrode and curve B represents the corresponding variations in current to the fourth electrode when the potential of the third electrode is varied, the potential of the fourth electrode being fixed at some suitable positive value. The portion of the curves between the limits R and S indicates the useful or operating range of the device. Between these limits the slope of the current-potential characteristic of the third electrode is negative and the slope of the corresponding current characteristic of the fourth electrode is positive but equal in value to that of the third electrode. Thus, the third electrode provides negative resistance and the fourth electrode provides a source of current variations equal in amplitude to variations which occur in the circuit of the third electrode without appreciably loading said circuit.

In Figure 3 I have illustrated a system in which a negative resistance device such as I have described above may be used to generate alternating currents of any desired frequency from a source of direct current. The electron discharge device 5 is constructed as shown in Figure 1. A battery 22 provides current for heating the filamentary cathode 10 and a battery 23 is employed to impress a constant positive potential upon the grid 12. The fourth electrode 18 is also connected to battery 23 through the primary winding 25 of a transformer 26. The secondary winding 27 of said transformer is included in some work circuit such as the antenna 28 of a radio transmitting system.

The circuit connecting the third electrode 14 to the cathode 10 includes a suitable portion of battery 23 and a resonant circuit consisting of inductance 29, capacitance 30, and resistance 31. The point 37 at which the third electrode is connected to battery 23 is so selected that the positive potential impressed upon the electrode 14 lies within the operating range of the device, that is, between the limits R and S shown in Figure 2.

If the value of the negative resistance in the third electrode circuit, as determined by the slope of the current-potential characteristic, is less than the equivalent parallel resistance of the resonant circuit, oscillations or pulsating currents will be generated in this circuit. Current variations of similar amplitude occur in the circuit which includes electrode 18 as described above and thus supply energy in the form of alternating currents to the work circuit.

The frequency of the oscillations generated is determined entirely by the constants of the resonant circuit which is associated with the third electrode. Variations in the nature of the work circuit have very little effect upon the generated frequency.

Since my device depends for its operation only upon the geometry of the electrodes comprising it and upon the fundamental properties of an electron stream, its characteristics can be varied to meet the requirements of specific applications by properly designing the form of the third electrode. In this respect my device offers distinct advantages over previously employed negative resistance devices based upon gas ionization or secondary emission effects, which have been found to be somewhat erratic in their operation and critical as to operating potentials.

Having thus described my invention and illustrated its use, what I claim as new and desire to secure by Letters Patent is:

1. In a device for producing alternating currents, in combination, a valving device comprising a highly evacuated receptacle, an electron emitting cathode therein, a grid adjacent to said cathode, said cathode and grid being connected to a source of difference potential, a third electrode in said receptacle comprising spaced plates lying adjacent to the path of electron emission from said cathode, said third electrode being connected through a resonant circuit to a portion of said source of difference of potential so as to be at positive potential with respect to said cathode, and a fourth electrode in said receptacle connected to a portion of said source of potential of greater positive potential than that impressed on said third electrode and forming part of an external work circuit, electrons emitted from said cathode passing between the plates of said third electrode in their path to the fourth electrode, whereby the current flow between said electrodes is varied inversely with the velocity of the electrons.

2. In a device of the character described, in combination, a thermionic device comprising a highly evacuated envelop, an electron emitting cathode in said envelop, a grid adjacent to said cathode, and an anode in said envelop, a negative resistance element interposed between the grid and said anode and comprising a plurality of substantially parallel inter-connected spaced metal plates lying parallel to the electron stream from said cathode to said anode, and means for impressing positive potentials on said grid, anode and element with respect to said cathode such that the portion of the electron stream intercepted by said parallel plates varies inversely with the potential applied thereto over the working range of the device.
